UNITED STATES PATENT OFFICE.

NAPOLEON DU BRUL, OF CINCINNATI, OHIO, ASSIGNOR TO THE MILLER, DU BRUL AND PETERS MANUFACTURING CO., OF CINCINNATI, OHIO, A CORPORATION OF OHIO.

CONTINUOUS CIGARETTE-MACHINE.

1,312,525.

Specification of Letters Patent. Patented Aug. 12, 1919.

Application filed July 26, 1916. Serial No. 111,456.

To all whom it may concern:

Be it known that I, NAPOLEON DU BRUL, a citizen of the United States, residing at Cincinnati, in the county of Hamilton and 5 State of Ohio, have invented certain new and useful Improvements in Continuous Cigarette-Machines, of which the following is a specification.

This invention relates to those portions of 10 a continuous cigarette machine in which the filler material is formed into a rope and delivered in proper relation to a paper strip to be inclosed thereby. More specifically, it relates to the mounting for the scraper plate 15 which is associated with the feed belt at the point where the tobacco leaves the belt and supports the tobacco rope as it passes over to the wrapper mechanism; also to the means for supporting and presenting the strip of 20 wrapper paper in proper relation to receive the rope of filler from the scraper plate, and which is made adjustable to bring the paper in the exact relation to the filler to insure proper completion of the wrapper.

25 It has long been the practice to locate a scraper immediately beyond the crest of the wheel that supports the belt beneath the rope-forming disks, with an edge of the scraper in feeding relation to the belt, for 30 the dual purpose of bridging the continuous body of tobacco from the belt to the wrapping mechanism, and of removing from the belt, particles of tobacco which might otherwise adhere and, accumulating, interfere 35 with the proper operation of the mechanism. Such scrapers, usually in the form of a steel plate, are subjected to severe wear, not only from the belt with which they coat and which is usually of steel, but also from the 40 tobacco which is appreciably abrasive in the condition in which it is fed; consequently, it is necessary to frequently adjust and at times to replace the scraper. But adjustment of these scrapers, as heretofore mounted, was not practicable without interrupting 45 the operation of the machine, while to remove a scraper and replace it with another, involved not only complete interruption of the operation, but more or less dis- 50 arrangement of other parts and thereby entailed an expenditure of time in addition to the inconvenience, which materially affected economy of production in the output of the machine.

55 One object of the present invention is to

provide an improved mounting for scraper plates of the kind referred to, which will not only permit adjustment of the scraper relatively to the belt without displacing other parts, or even the interruption of the tobacco feed, but will greatly facilitate removing and replacing the scraper when necessary. Accordingly, one feature of the present invention consists in mounting the scraper, not upon a portion of the machine 60 located beneath the line of feed, but through the medium of a bracket which extends laterally away from the line of feed and is secured upon a support afforded by a substantial portion of the machine to one side of 70 the belt; this bracket being adjustably secured to permit setting up the scraper toward the belt as the scraper wears away, and being readily detachable and adapted to bring away the scraper blade with it, so 75 that it can be removed and have a new blade applied to it, and then replaced in position without disarranging other parts.

In machines of the class described, it is necessary to not only provide guide rollers 80 for the paper strip and its supporting tape, but to locate these rollers as close as practicable to the center line of the compression disks which renders the rollers comparatively inaccessible, but it is necessary that 85 their adjustment be imparted to them during the running of the paper strip, in order that the position of the paper may be observed in its relation to the wrapper tube, and it is very desirable to permit the tape 90 and the paper to be placed over the ends of their respective guide rollers, in placing them in position, as distinguished from threading them through the parts.

Another object of the present invention is 95 to provide mountings for the tape and paper guide rollers, through means of which the aforesaid several conditions of assembly and adjustment may be realized in a simple but efficient manner. Accordingly, another fea- 100 ture of the present invention consists in supporting these guide rollers upon spindles which project transversely of the line of feed, from the ends of angle arms whose supporting ends lie transversely of the line 105 of feed and receive pivots upon which the arms are mounted, while their other ends extend longitudinally of the machine or at such other angles to the supporting ends as will bring them under the control of adjust- 110

- ing and clamping means within convenient reach of the operator, and cause an adjustment and fixing of these adjusting ends, to result in the assumption of new angular positions of the guide rollers, relatively to the line of feed, and consequently drive the paper strip and supporting tape to one side or the other of the wrapper tube and position it accurately with relation to the pasting or other form of sealing means.
- 10 In machines of the class described, it is very desirable to provide a tape tensioning means, and it is also desirable to adapt such tensioning means to yield to an abnormal pull on the tape and to automatically resume its position and reestablish the predetermined tension of the tape, as soon as the disturbing condition (for instance a lump in the tobacco) has passed.
- 20 Another object of the present invention is to provide a tape tensioning means readily adjustable at will to establish any desired tension to be normally imparted to the tape, but holding said tension yieldingly and re-
- 25 turning to said tension automatically in case of a temporary disturbing condition in the filler material. Accordingly, another feature of the invention consists in providing a pair of rollers around which the tape
- 30 is deflected, mounting these rollers in a rocking frame (preferably in the form of a yoke centered upon a rock shaft), so that the deflection of the tape may be increased or decreased at will, providing said shaft with
- 35 means for adjusting it, such for instance as a worm wheel and a worm, angular toothed gears or the like, and sustaining the adjusting spindle of the worm or gear through the means of a spring, so that whatever the
- 40 angular position imparted to the deflecting rollers, to take up slack in the tape, the adjustment will be held yieldingly and re-established automatically, in case an obstruction passes through the wrapper tube.
- 45 The invention will be fully understood upon reference to the accompanying drawings, in which—
- Figures 1 and 2 are, respectively, a top plan view and a side elevation of the portion of a continuous cigarette machine with which the present invention is immediately concerned;
- 50 Fig. 3 is a detail perspective view of the scraper blade and its supporting bracket;
- 55 Fig. 4 is a detail perspective view showing the scraper blade, the tape and paper guide rollers, the mountings for these parts, and the portions of the machine with which they are immediately associated.
- 60 1 represents the feed belt, commonly made of steel, 2 the guide wheel for said belt, 3 of the laterally acting pressure disks mounted with the transverse line of their axes over the crest of the wheel 2, 4 the mounting for

one of said disks, 5 the wrapper tube mounting, 6 the tape, and 7 the tape wheel, all of which parts may be constructed in a manner well known in the art prior to the date of the present application.

Supported from some suitable portion of the machine frame, such for instance as the mounting 4, is a table 8 (Fig. 1) to one side of the belt guiding wheel 2 and extending sufficiently forward of the crest of said wheel, in the direction of feed to serve as a support for a belt scraper blade. Mounted upon the table 8 is a bracket 9 having an attaching head 10 and a supporting arm 11, projecting laterally from the table 8 to a position overhanging the belt wheel 2, and having detachably secured upon its overhanging portion, the scraper blade 12. The attaching head 10 is elongated in the direction of the belt 1 to secure the bracket 9 against tipping under the friction applied at its scraping end, and this head is detachably held in position by means of screws 13, or equivalent means, passing through said head and the table 8; the openings in one of said parts being elongated to permit the bracket to be moved longitudinally of the belt and thus bring the scraping edge of the blade 12 into proper relation to the belt. The elongated openings are preferably through the table 8, and the screws 13 are introduced from below, through said openings and have their upper ends threaded into the head of the bracket.

The supporting arm 11, which preferably lies beneath the blade 12, is beveled as at 11^a, on the side adjacent to the belt, so as to permit close adjustment of the blade to the belt, and the forward end of the blade 12 is beveled, as shown at 12^a, so as to not only maintain an efficient scraping edge next to the belt, but to provide a level surface in continuation of the belt over which the tobacco will flow without obstruction, passing from the belt to the wrapping mechanism.

From the foregoing description, it will be seen that the blade 12 can be adjusted relatively to the belt 1, without disarranging any of the parts, by merely loosening the screws 13 and setting up the bracket toward the belt, this being done even while the stream of tobacco is continuing across the blade if desired, and if it becomes necessary to replace the blade, it is merely necessary to remove the bracket 9 with its attached blade, apply a new blade thereto, and replace the bracket in position without disarranging any of the other parts.

The tape guide roller 14 and the paper guide roller 15 are mounted upon the spindles 16 and 17 which project axially from the transverse arms 18^a and 19^a of the supporting members 18 and 19, which are piv-

oted at 20 and 21 in their said transverse arms and have angularly extending arms 18^b, 19^a, presented in such positions (preferably at right angles to the arms 18^a, 19^a) as will 5 render them conveniently adjustable by the screws 22, 23, having turning heads 24, 25, and threaded in the wall 26 in position to bear against said arms 18^b, 19^b, and develop angular adjustment in the spindles 16, 17. 10 Screws 28, 29, projecting through slots 30, 31, in the arms 18^b, 19^b, and receiving clamping nuts 32, 33, provide for locking the roller supports in any angular position to which they may be adjusted. These parts 15 may be mounted upon any conveniently available substantial portion of the machine to one side of the line of feed, such for instance as the wrapper tube bracket 27, and when constructed and arranged as above described, will afford simple and efficient means for conveniently developing minute angular adjustments in the tape and paper rollers which are so important to the perfect working of a continuous cigarette machine. 20

In order to yieldingly maintain a predetermined adjustment in the tension of the tape 6, and automatically reestablish such adjustment in the event of temporary disturbance of the same, the tape is passed around the deflecting rollers 34, mounted in a yoke 35 upon the rock shaft 36, which has fixedly mounted upon it, at a convenient point, a gear wheel 37 coacting with a suitable gear wheel or worm 38, whose spindle 39 is adapted to be rotated by the head 40 in order to develop angular adjustments in the shaft 36 and yoke 35. Movement of the yoke 35 in the direction to slacken the tape, 30 would develop a downward pull on the spindle 39 and this downward pull is resisted by a compression spring 41 which surrounds the spindle. As a consequence of this arrangement, any temporary condition 35 developing an abnormal pull upon the tape would be permitted to swing the yoke 35 and reduce the deflection or take-up in the tape, compressing the spring 41 in so doing, and this would relieve the tape until the obstruction passed. But as soon as the obstruction passes, the spring 41 reestablishes 40 the predetermined positions of the parts and consequently the desired tension on the tape or that suitable for the normal operation of 45 the machine.

I claim:—

1. In a cigarette machine having a feed belt, a scraper for said belt having a bracket-like mounting supported and accessible for 50 movement at one side of the feed belt and unattached at the other side.
2. In a cigarette machine having a feed belt, a scraper positioned to coact with the feed belt and extending laterally from the 55 feed belt, and a bracket-like support for

said scraper at one side of the feed belt, upon which said scraper is adjustable and unattached at the other side of the feed belt.

3. In a cigarette machine having a feed belt, a scraper positioned to coact with the 70 feed belt and extending laterally from the feed belt, and a support for said scraper at one side of the feed belt, upon which said scraper is adjustable; said scraper comprising a blade lying in the plane of the belt, 75 and a bracket to which said blade is attached extending laterally from the blade to the support.

4. In a cigarette machine having a feed belt, a scraper positioned to coact with the 80 feed belt and extending laterally from the feed belt, and a support for said scraper at one side of the feed belt, upon which said scraper is adjustable; said scraper comprising a blade lying in the plane of the belt, 85 and a bracket to which said blade is attached extending laterally from the blade to the support; said bracket being constructed with a blade-supporting arm and an attaching

90

5. In a cigarette machine having a feed belt, a scraper positioned to coact with the feed belt and extending laterally from the feed belt, and a support for said scraper at one side of the feed belt, upon which said 95 scraper is adjustable; said scraper comprising a blade lying in the plane of the belt, and a bracket to which said blade is attached extending laterally from the blade to the support; said bracket being constructed with 100 a blade-supporting arm and an attaching base; said supporting arm and blade, adjacent to the belt, being beveled to conform to the belt.

6. In a cigarette machine having a feed 105 belt, a scraper positioned to coact with the feed belt and extending laterally from the feed belt, and a support for said scraper at one side of the feed belt, upon which said scraper is adjustable; said scraper comprising a blade lying in the plane of the belt, and a bracket to which said blade is attached extending laterally from the blade to the support; said bracket being constructed with a blade-supporting arm and an attaching 110 base; said attaching base being elongated in the direction of the belt.

7. In a cigarette machine having a feed belt, a scraper positioned to coact with the feed belt and extending laterally from the 120 feed belt, and a support for said scraper at one side of the feed belt, upon which said scraper is adjustable; said scraper comprising a blade lying in the plane of the belt, and a bracket to which said blade is attached 125 extending laterally from the blade to the support; said bracket being constructed with a blade-supporting arm and an attaching base; said attaching base being provided with securing means uniting the base with 130

its support, and screws entering slots in one of the parts to permit adjustment of the bracket in the direction to set the scraping edge of the blade up to the belt.

5 8. In a cigarette machine having a tobacco feeding belt and disks acting upon the tobacco fed by said belt, a scraper blade positioned to coat with the belt at a point beneath the disks, a supporting table located beneath one of said disks and to one side of the belt, and a bracket adjustably supported on said table and projecting beneath the scraper blade.

15 9. In a cigarette machine, the combination with a tape for feeding tobacco, of a tensioning device comprising a guide roller for said tape, and a mounting for said guide roller comprising an arm lying substantially transversely to the travel of the tape, having a 20 pivotal mounting upon the machine, carrying the guide roller upon one end thereof, and having beyond its pivot, an adjusting arm with means for adjusting it and shifting the mounting upon its pivot.

25 10. In a cigarette machine, the combination with a tape for feeding tobacco, of a tensioning device comprising a guide roller mounted transversely to the tape, and a support for said guide roller comprising an angle bar having an arm lying transversely 30 of the machine, with the guide roller projecting axially therefrom, and with a pivot in said transversely lying arm, and adjusting means coacting with said support.

35 11. In a cigarette machine, the combination with a tape for feeding tobacco, of a tensioning device comprising a guide roller and means for supporting said roller with angular adjustment comprising an angle 40 bar having one arm in alinement with the guide roller and pivotally mounted through the medium of said alining arm, and having another arm extending at an angle to said alining arm and provided with adjusting 45 means acting transversely thereon.

12. In a cigarette machine, the combination with a tape for feeding tobacco, of a tensioning device comprising an angle bar having a transverse arm and a longitudinal 50 arm, pivotally mounted upon the machine through the medium of its transverse arm, a guide roller projecting axially from the end of the transverse arm, and an adjusting screw acting transversely upon the longitudinal arm.

55 13. In a cigarette machine, the combina-

tion with a tape for feeding tobacco, of a tensioning device comprising an angle bar having a transverse arm and a longitudinal arm, pivotally mounted upon the machine 60 through the medium of its transverse arm, a guide roller projecting axially from the end of the transverse arm, and an adjusting screw acting transversely upon the longitudinal arm; said angle bar having means for locking it in positions to which it may be adjusted.

14. In a cigarette machine, the combination with a paper strip tape, and a tensioning device comprising a pair of angle bars 70 each having a transverse arm and a longitudinal arm and independently pivoted upon the machine through the medium of their respective transverse arms, a tape guide roller and a paper guide roller projecting 75 axially from the respective transverse arms, and a pair of adjusting members acting independently and in a transverse direction upon the respective longitudinal arms of the bars.

80 15. In a cigarette machine, the combination with a tape for feeding tobacco, of a tensioning means comprising deflecting rollers, a mounting for said rollers adjustable to vary their angular relation to the line of 85 the tape and thereby vary the tension upon the tape, means for imparting adjustment to said rollers, and a yielding support for the adjusting means.

16. In a cigarette machine, a tape tensioning means embodying a guide roller around which the tape is deflected, having a swinging movement to vary the deflection of the tape, a sustaining spindle resisting 90 said swinging movement, and a resilient support for said spindle, yielding to permit swinging movement of the roller under an abnormal pull upon the tape.

95 17. In a cigarette machine, the combination with a tape for feeding tobacco, of a 100 tape tensioning means comprising a yoke, deflecting rollers mounted on said yoke, a shaft supporting said yoke, a gear wheel on said shaft, an adjusting member for said gear wheel, an adjusting spindle for said 105 adjusting member, and a spring sustaining said adjusting spindle in the direction of its axis.

The foregoing specification signed at Cincinnati, Ohio, this 21st day of July, 1916. 110

NAPOLEON DU BRUL.
